UNITED STATES PATENT OFFICE.

ERNEST GOTHLBERG, OF JERSEY CITY, NEW JERSEY.

DESIGN FOR A CHANDELIER-BODY.

No. 38,573.

Specification for Design.

Patented May 14, 1907.

Application filed March 22, 1907. Serial No. 363,992. Term of patent 7 years.

To all whom it may concern:

Be it known that I, ERNEST GOTHLBERG, a citizen of the United States, and a resident of Jersey City, in the county of Hudson and State of New Jersey, have invented a new, original, and ornamental Design for Chandelier-Bodies, reference being had to the accompanying drawing, in which the figure shown therein is an isometric view of the body.

I claim:
The ornamental design for a chandelier body, as shown.

ERNEST GOTHLBERG.
